(57) **CLAIM**

The ornamental design for a pair of shoe soles, as shown and described.

DESCRIPTION

FIG. 1 is a bottom orthogonal view of a pair of shoe soles according to my new design.

FIG. 2 is a bottom rear perspective view thereof; and, FIG. 3 is a bottom front perspective view thereof.

The subject matter in dotted lines is shown for clarification and forms no part of the claimed design subject matter.

1 Claim, 3 Drawing Sheets

FIG. 1

FIG. 2

FIG. 3
